148,817

DESIGN FOR A LAMP

Edward P. Poore and Jay O. Wagner,
Sandusky, Ohio

Application December 3, 1946, Serial No. 135,218

Term of patent 7 years

(Cl. D48—20)

To all whom it may concern:

Be it known that we, Edward P. Poore and Jay O. Wagner, citizens of the United States, residing at Sandusky, in the county of Erie and State of Ohio, have invented a new, original, and ornamental Design for Lamps of which the following is a specification, reference being had to the accompanying drawing, forming part thereof, wherein:

We claim:

The ornamental design for a lamp, substantially as shown.

EDWARD P. POORE.
JAY O. WAGNER.
